CLAIM

The ornamental design for an automobile tire, as shown and described.

DESCRIPTION

FIG. 1 is a front view of an automobile tire;

FIG. 2 is a rear view thereof;

FIG. 3 is a left-side view thereof;

FIG. 4 is a right-side view thereof;

FIG. 5 is a perspective view thereof;

FIG. 6 is a reference front view thereof, shown with a portion of the groove area shown in black; and,

FIG. 7 is a cross-section view thereof, taken along line 7—7 in FIG. 6 and shown at an enlarged scale.

The broken lines depict environmental subject matter only and form no part of the claimed design.
